UNITED STATES PATENT OFFICE.

THOMAS J. MURFIN, OF SLEEPY EYE, MINNESOTA.

DRAINABLE PIPE FOR TANKS.

SPECIFICATION forming part of Letters Patent No. 605,295, dated June 7, 1898.

Application filed December 14, 1897. Serial No. 661,832. (No model.)

To all whom it may concern:

Be it known that I, THOMAS J. MURFIN, a citizen of the United States, residing at Sleepy Eye, in the county of Brown and State of Minnesota, have invented certain new and useful Improvements in Drainable Pipes for Tanks; and I do hereby declare the following to be a full, clear, and exact description of the invention, such as will enable others skilled in the art to which it appertains to make and use the same.

My invention was especially designed for use in connection with gasoline or other water-jacketed engines, but is capable of use generally wherever the corresponding function is required.

With the class of engines above referred to the water is supplied usually from a suitable tank, which is provided with circulating connections to the jacket of the engine-cylinder. These tanks are frequently exposed to low temperatures at times when the engine is not in use. Under such conditions much difficulty has been experienced with the circulating-pipes on account of the freezing of the water therein.

My invention has for its object to provide a pipe or pipes for use in connection with a water or other liquid tank which shall be of such construction as to permit the pipe to be emptied without emptying the tank.

To this end my invention consists of the novel features of construction hereinafter described, and defined in the claims.

The invention is illustrated in the accompanying drawings, wherein like notations refer to like parts throughout the several views.

Figure 1 is an end elevation of a gasoline-engine plant with some parts removed and others broken away. Fig. 2 is a similar view of the water-supply tank and part of the circulating connections, but with the sections of the pipes within the tank in their idle or draining position. Fig. 3 is a view of a tank equipped with a single pipe constructed in accordance with my invention, illustrating the general application of the same, whether or not the same be combined with a water-jacketed engine.

The numeral 1 indicates an ordinary gasoline-engine, and the numeral 2 denotes the water-jacket thereof.

The numeral 3 represents a suitable tank for holding the water required to water-jacket the engine. The said tank is shown as upheld by a suitable support 4 at the proper level for the work required. The supply-pipe from the water-jacket 2 of the engine is shown as made up of the sections a' , a^2 , a^3 , and a^4 . The return-flow pipe is shown as made up of the sections b' , b^2 , b^3 . The section a^4 of the supply-pipe is shown as tapped by a waste-pipe c , which is provided with a suitable stop-cock c' . The feature of novelty about these circulating-pipes above noted is the fact that the section a' of the supply-pipe and the section b^3 of the return-flow pipe are flexible, the same being shown as made up of ordinary hose. Normally these flexible sections of the circulating-pipes located within the tank 3 are submerged, and the circulating connections then operate in the ordinary way when the engine is at work. When the engine is stopped, if the season and exposure be such as to require care to avoid freezing of the water in the pipes, the flexible sections within the tank may be elevated into such a position that their upper ends will be out of the water and that gravity will become operative to drain the pipes whenever a suitable outlet is afforded. For the engine plant the waste-pipe c and stop-cock c' will afford such an outlet when the stop-cock c' is turned into its open position. Any suitable means may be provided for raising the flexible pipe-sections c' and b^3 into their elevated or draining position, as shown in Fig. 2. The means shown for the purpose are ordinary pull-ropes or flexible connections f , extending to the outside of the tank and which may be made fast to any suitable retaining devices, such as the headed pins or set-screws f' , fixed to the side of the tank. When the said flexible pipe-sections are in the position shown in Fig. 2 and stop-cock c' is open, it is obvious that all the water within the pipe, as well as the water within the engine-jacket 2, will be permitted to escape, under the action of gravity, through the waste-pipe c . Hence no freezing of water can occur within the circulating-pipes.

The quantity of water within the tank 3 is usually sufficient to prevent any serious injury from the ordinary amount of freezing

to which the same is subjected under ordinary conditions. The trouble has been with the freezing of the water in the circulating-pipes and the consequent bursting of the pipes. In the old construction a stop-cock has usually been placed in the pipe-section a^2 , projecting from the bottom of the tank, and when the engine was stopped this stop-cock was turned into its closed position in order 10 to permit the water-jacket 2 of the engine and the other parts of the circulating-pipes to be drained through the waste-pipe c , and with that old construction the pipe-section a^2 would burst at or near the tank or on the 15 water-side of the stop-cock formerly employed. It is obvious that with my improvement this trouble is avoided.

It will readily be understood that the same principle of construction is capable of application to tanks and liquid-containing vessels 20 of all kinds wherever the corresponding function is required. In the construction shown in Fig. 3, for example, the tank and its support are shown as supplied with a single pipe, 25 shown as made up of the sections a' and a^2 only, with the section a^2 open for discharge into the atmosphere. It is obvious that with this construction the action is the same as in the plant above described so far as draining 30 the outlet-pipe is concerned. With the form shown in Fig. 3 the flexible pipe-section or 35 hose a will be submerged and drop to the bottom of the tank when it is desired to empty the tank for any purpose, and when it is desired to drain the pipe without emptying the tank the flexible or hose section a will be drawn up into the position illustrated.

The tank as illustrated in Figs. 1 and 2 is shown as provided with an overflow-pipe g 40 near its top.

The hose or flexible sections of the pipes within the tank are of sufficient weight to sink into their normal or submerged positions in water under the action of gravity; but if any 45 denser liquids were employed or any difficulty in that respect was experienced the pipe-sections a' and b^3 could be loaded with sufficient weight in any suitable way.

The flexible pipe sections or section within the tank is the best construction according to 50 my experience and judgment, and I do not know of any other which is the full mechanical equivalent thereof; but pipe-sections might be otherwise made extensible—such, for example, as sections having screw-threaded engagement with each other below the water-level and extensible one on the other to bring the mouth of the pipe above the liquid-level in the tank.

What I claim, and desire to secure by Letters Patent of the United States, is as follows:

1. The combination with a tank for water or other liquids, of a pipe having, within the tank a section normally submerged, but capable of extension to a point above the liquid-level in the tank, for draining the pipe without emptying the tank, substantially as described.

2. The combination with a tank and an engine having a water-jacket, of circulating 70 connections from said tank to said jacket, which circulating connections include sections of pipe within the tank normally submerged, but capable of extension to a point above the liquid-level, and a discharge-opening, outside the tank, for draining the circulating connections in the water-jacket of the engine, without emptying the tank, substantially as described.

3. The combination with a water-tank and 80 a water-jacketed engine, of circulating connections from the tank to the engine, which connections are provided with flexible sections of pipe within the tank normally submerged, but capable of being elevated to 85 bring their mouths above the liquid-level in the tank, and a valve-controlled discharge-opening, at the lowest point in the circulating connections outside the tank, substantially as and for the purposes set forth.

In testimony whereof I affix my signature in presence of two witnesses.

THOMAS J. MURFIN.
